UNITED STATES PATENT OFFICE.

GEORGE W. MYERS, OF PHILADELPHIA, PENNSYLVANIA.

RATCHET-WRENCH OUTFIT.

Application filed July 29, 1926. Serial No. 125,645.

This invention relates to tools, particularly to wrenches, and has for its object the provision of a novel reversible ratchet wrench in conjunction with which may be employed bit elements of various types such as socket wrenches of any size, screw drivers or the like, the intention being to provide a sufficient number of bit elements that work of different kinds may be done on or about machinery or the like.

An important object of the invention is to provide a wrench of this character which may be so constructed that by its use access may be had to parts which are ordinarily hard to reach or impossible to reach by means of the usual monkey wrench, open end wrench or the like.

A very important object of the invention is to provide a ratchet wrench which is reversible and which embodies a pair of selectively usable pawls cooperating with a ratchet for effecting turning movement of whatever tool or bit is used, novel means being provided for holding a selected one of the pawls inoperative or out of engagement with the ratchet, depending upon the desired direction of rotation.

A further object is the provision of a wrench of this character in which the rotary element or socket member is provided with novel means permanently carried thereby for holding a bit or other tool member positively against displacement or dropping out, this retaining means being of such nature as to obviate any necessity for the employment of an elaborate chuck mechanism.

An additional object of the invention is to provide a device of this character which will be simple and inexpensive in manufacture, easy to adjust and operate, rapid in action, efficient in use, durable in service, and a general improvement in the art.

With the above and other objects and advantages in view, the invention preferably consists in the arrangement and combination of parts and detailed structural features to be hereinafter more fully described and claimed, and illustrated in the accompanying drawings in which:

Figure 1 is a side elevation of the wrench showing a socket wrench bit member carried thereby,

Figure 2 is an elevation of a screw driver which may be used instead of the wrench bit or member,

Figure 3 is an elevation of a lengthening bar which may be interposed between the wrench and any of the bit members used in connection therewith,

60

Figure 4 is a fragmentary sectional view through the socket end of the lengthening bar showing the screw driver member engaged therein,

Figure 5 is a similar view showing a 65 socket wrench member or bit engaged with the lengthening bar,

Figure 6 is a cross section taken on the line 6—6 of Figure 3,

Figure 7 is a plan view of the wrench or 70 elevation taken at right angles to Figure 1,

Figure 8 is a horizontal section taken on the line 8—8 of Figure 1,

Figure 9 is a longitudinal section taken on the line 9—9 of Figure 8, and

75

Figure 10 is a cross section taken on the line 10—10 of Figure 7.

Referring more particularly to the drawings, I have shown the wrench as comprising an elongated shank 15 provided at one end with a suitable handle 16 preferably shaped so as to be comfortable in the grasp of the operator. The other end of the shank is enlarged to define a head 17, the juncture of the head with the shank being formed preferably with spaced pairs of ears or lugs 18 which project laterally as clearly indicated in Figure 7. The head is formed in its sides with grooves or recesses 19 which extend from substantially the ears 18 and which lead into an opening 20 extending entirely through the head as clearly shown in Figure 8. The provision of the opening 20 actually defines what may be called arms 21 and 22 at opposite ends of the opening, the former being provided with a hole 23 and the latter with a hole 24 of larger diameter.

80

The provision of the opening 20 actually defines what may be called arms 21 and 22 at opposite ends of the opening, the former being provided with a hole 23 and the latter with a hole 24 of larger diameter.

90

The numeral 25 designates the rotatable member of the wrench, this member being journaled through the head 17 and terminating at one end in a reduced extension 26 rotatable through the hole 23. The other end portion of the member 25 is rotatable within the hole 24 and of course projects beyond the side of the head. That portion of the member 25 located within the confines of the opening 20 is enlarged and provided with grooves 27 which define a ratchet structure. This enlarged intermediate portion of the member 25 prevents longitudinal movement thereof in one direction, and movement in the other direction is prevented by

100

105

110

means of a cotter pin 28 or the like passing through the reduced extension 26 and engaging against a suitable washer 29. The member 25 is formed with a socket 30 extending longitudinally thereof and throughout a portion of the length, this socket being provided for holding a desired tool or bit member as will be explained.

Located at opposite sides of the head and pivoted between the pairs of ears 18, as shown at 31, are elongated pawls 32 having reduced end portions 33 curved toward each other and cooperating with the grooves 27 in the member 25 for constituting a driving connection for effecting rotation of the latter when the handle is moved back and forth. These pawls 32 are urged toward each other or into operative relation to the member 25 as by means of a coil spring 34 which extends through a transverse opening 35 in the head and which has its ends connected with ears 36 on the confronting faces of the pawls.

Whenever the device is in use, as a ratchet wrench, it is of course necessary that one of the pawls be held in inoperative position or out of engagement with the member 25. In carrying out this feature of the invention I form the opposite sides of the head 17 with a transversely arranged grooves 37 within a selected one of which may be engaged a removable wedge 38, the confronting edges of the pawls being preferably slightly recessed as indicated at 39 so as to guide the wedge 38 when it is inserted in place. The wedge member preferably has a curved end 40 facilitating its insertion between the head and either of the pawls 32. In order to avoid loss of the wedge member 38, I preferably provide a flexible member 41 connected therewith and connected at its other end with a suitable anchor 42 on the head.

In connection with the wrench above described, it is of course conceivable that I may make use of any desired or suitable bit member, depending upon the exact work to be done. In case it is desired to turn a bolt or nut, I employ the bit member shown at 43, this bit member being formed at one end with a reduced extension 44 angular in cross section and fitting slidably within the bore or socket 30 and held therein as by a pin 45 insertable transversely through a suitable hole in the projecting portion of the member 25 and through a hole 46 in the reduced extension 44, the pin being preferably carried by a flexible member 47 which will prevent loss. Clearly, in actual practice, there will be provided a plurality of the members 43 formed with sockets 48 of different sizes so as to be capable of taking care of bolts and nuts of widely different sizes.

If the device is to be used for turning screws, the bit member 43 would be replaced by a bit member 49 shown in Figure 2 hav-

ing a reduced extension 50 adapted to fit within the socket or bore 30, the extension being provided with a hole 51 for the passage of the pin 45. The bit member 49 has a reduced flattened end 52 constituting a screw driver.

In some instances, as when nuts, bolts, screws or the like are in ordinarily inaccessible places, I may make use of a lengthening bar 53 of suitable length, this bar being adapted for interposition between the wrench and the selected bit member. The extension bar 53 is of course provided with a reduced extension 54 adapted to fit within the bore or socket 30 and provided with a hole 55 for the reception of the pin 45. The other end of the extension bar 53 is enlarged as shown at 56 and is formed with a socket 57 corresponding to the socket 30 and adapted to receive the reduced extension 44 of the bit member 43 or the reduced extension 50 of the bit member 49. The enlarged portion 56 has a hole 58 therein for the reception of a locking pin 59 connected with the member 53 by a flexible member 60 and acting in exactly the same manner as the pin 45.

In the operation of the device, it will be seen that the desired bit is first engaged with the wrench and is of course engaged with the nut, bolt or screw to be turned. The wedge member 38 is then inserted in place to hold either of the pawls 32 out of engagement with the ratchet, depending upon whether it is desired to turn the bolt, nut or screw to the right or the left. This having been done, the operator grasps the handle 16 and swings the wrench back and forth to effect the turning action, the other pawl which is left in cooperative relation to the ratchet acting to impart turning movement to the member 25 and consequently to the bit and machine element engaged thereby. If a ratchet action is not desired, the wedge member 38 may be left idle or not engaged with either pawl 32, whereupon both pawls will engage the ratchet and the wrench be a rigid one. It is really believed that the construction, operation and advantages will be readily apparent to one skilled in the art without further explanation.

While I have shown and described a preferred embodiment of the invention, it should be understood that I reserve the right to make such changes in the form, construction and arrangement of parts as will not depart from the spirit of the invention or the scope of the subjoined claims.

Having thus described the invention, I claim:

1. A wrench of the character described comprising an elongated shank having one end constituting a handle and terminating at its other end in a head having an open-

ing therethrough and formed with grooves in the opposite sides leading into the opening, a member rotatably mounted within the head at the opening therein and formed as 5 a ratchet, said member projecting beyond one side of the head with said projecting portion socketed for the reception of a bit element, a pair of pawls pivoted at the juncture of the head of the shank and spring 10 pressed toward said ratchet member, the opposite sides of the head being formed with grooves transversely of and leading into said first named grooves, and a wedge member 15 engageable within a selected one of the second named grooves for holding a selected pawl out of engagement with said ratchet member.

2. A wrench of the character described comprising an elongated shank having one 20 end constituting a handle and terminating at its other end in a head having an opening therethrough and formed with grooves in the opposite sides leading into the opening,

a member rotatably mounted within the head at the opening therein and formed as 25 a ratchet, said member projecting beyond one side of the head with said projecting portion socketed for the reception of a bit element, a pair of pawls pivoted at the juncture of the head with the shank and spring 30 pressed toward said ratchet member, the opposite sides of the head being formed with grooves transversely of and leading into said first named grooves, and a wedge member 35 engageable within a selected one of the second named grooves for holding a selected pawl out of engagement with said ratchet member, the second named grooves terminating at the far side of the first named grooves, and the end of the wedge member 40 being curved to facilitate its insertion between the bottom of the second named groove and the adjacent face of the pawl member to be held inactive.

In testimony whereof I affix my signature.
GEORGE W. MYERS.
